Primary Examiner—James Gandy*Attorney, Agent, or Firm*—Finnegan, Henderson, Farabow, Garrett & Dunner, L.L.P.**[57] CLAIM**

The ornamental design for a pattern for absorbent sheet material, as shown and described.

DESCRIPTION

FIG. 1 is a plan view of a first embodiment of the pattern of the invention; and,

FIG. 2 is a plan view of a second embodiment of the pattern. The broken line boundary of the claimed design indicates that the design has indeterminate length and width, it being understood that the pattern repeats uniformly throughout the design.
